UNITED STATES PATENT OFFICE.

FREDERICK G. SARGENT, OF WESTFORD, MASSACHUSETTS, ASSIGNOR TO C. G. SARGENT'S SONS CORPORATION, OF GRANITEVILLE, MASSACHUSETTS, A CORPORATION OF MASSACHUSETTS.

PUMP FOR WOOL-WASHING MACHINES.

1,128,056.

Specification of Letters Patent.

Patented Feb. 9, 1915.

Application filed April 15, 1914. Serial No. 832,104.

To all whom it may concern:

Be it known that I, FREDERICK G. SARGENT, a citizen of the United States, residing at Westford, in the county of Middlesex and 5 State of Massachusetts, have invented a new and useful Pump for Wool-Washing Machines, of which the following is a specification.

This invention relates to the discharge of 10 the liquor from the catch basin under the press rolls of a wool washing machine into the settling tank thereof.

The principal objects of the invention are to provide for accomplishing this operation 15 in such a way as to avoid the churning and foaming of the liquor; to avoid stirring up the sediment in the bottom of the catch basin from which the liquor is drawn; to deliver the liquor into the settling tank in a smooth 20 and easy manner; and at the same time to provide an apparatus for this purpose which shall have no valves to clog up and no small parts that can catch the fibers and thus have their efficiency reduced.

25 The invention also involves improvements in details of construction and combinations of parts as will appear hereinafter.

Reference is to be had to the accompanying drawings in which—

30 Figure 1 is a perspective view of a portion of a wool washing machine with a preferred embodiment of this invention applied thereto; Fig. 2 is a sectional view of the same on a vertical plane parallel to the side of the 35 tank through the central axis of the pump; and Fig. 3 is a side elevation of one of the sections of the pump.

The pumping of the liquor from the catch basin of a wool washing machine to the 40 settling tank is an operation that presents considerable difficulty. This liquor has soap and alkali dissolved in it and also contains wool fibers and a great deal of sediment. The ordinary lift pump is not suitable for 45 this purpose because its valves clog up with mud and sediment in a short time and further on account of the plunging action which churns up the liquor and causes it to froth the foam. The fibers also get into the 50 valves and act similarly to the sediment. This foaming action is a condition to which 55 this liquor is especially subject on account of the materials put in to wash the wool. The chain bucket pump is somewhat better but it also produces the churning action and

introduces other complications on account of the travel of the buckets through the long tube which they must lift. In order to avoid these difficulties it has been customary to use a centrifugal pump but this, while avoiding the use of the valves of the lift pump, does not lessen the churning and frothing. Consequently when used the scouring liquor is churned up into a foam to such an extent that when it is delivered into the settling 60 tank it tends to foam over the sides. In this way much valuable scouring soap is wasted. To prevent this loss it is customary to cover or seal the tops of the settling tanks. I have discovered that by the use of a helical screw 65 pump constructed in a certain way all this excessive foaming is avoided; the liquor is left in a better condition in the settling tank to allow the impurities to settle; the sediment in the catch basin is not stirred up; 70 the cover over the settling tank is dispensed with; and a greater settling of dirt in the settling tank is secured. Of course this is the prime, and in fact the only object of this tank. 75

Referring now to the accompanying drawings, it will be seen that the invention is applied to a wool washing tank *a* of ordinary construction having a set of press rolls *b* provided with a catch basin *c* under the 80 same for catching the liquor therefrom. The settling tank *b* is provided along the side of the main tank. The problem is to get the liquor from the catch basin, or at least that part of it which does not settle at the bottom 85 in the form of a sediment, into the settling tank in such condition that it will not stir up the liquor already in there so that the settling operation may take place with the greatest efficiency and speed. The settling 90 tank of course delivers back into the bowl in the usual way. For the purpose of accomplishing these results the catch basin is provided with an outlet 10 near the top connected through a pipe 11, preferably horizontal, into the inlet 12 of a stationary 95 cylindrical casing 13. This casing is located at the side of the settling tank and its inlet is located above its bottom for a purpose which will appear. At the bottom of this 100 casing is a step 14 having a conical top 15. On this step is a seat 16 preferably of phosphor bronze or the like having a conical recess in the bottom fitting the cone 15 and securely fixed to the bottom of a shaft 17. 105

This shaft is centrally located in the casing and extends up through the top thereof where it is provided with a driving pulley 18. This shaft is provided throughout its 5 length above the seat with a helical blade 20. This blade is made up of a plurality of sections which consist of a hollow cylinder 21 fixed to the shaft and a section of the blade 20 cast integral therewith. Each of these 10 sections preferably goes entirely around the shaft. These sections can be strung on the central shaft and fastened thereto by set screws so as to make a complete helix. The bottom end of each section of the helix fits 15 the top end of the next one secured below. This forms a convenient construction for manufacture and permits ready repairs. The seat and step also can be removed and replaced readily in case of wear.

20 It will be noted that the bottom of the helix, including the entire lower convolution, goes down below the bottom of the inlet 12 so that there is a natural head of water above the first complete convolution 25 of the helix. It will also be noted that the edge of the blade constituting this convolution of the helix, that is, the lower section, is sharpened. Now when the shaft rotates the helix, which fits the inside of the cylinder, is rotated and the liquor lifted gently 30 and uniformly without causing any pulsating action either at the inlet or the outlet. In this way a steady stream of liquor is drawn off from the catch basin and passes 35 away from it in the same manner as would be the case if it were allowed to flow out by gravity. The same condition prevails at the outlet 23 from which the liquor is delivered by the same easy motion into the top of the 40 settling tank. It will be noted that this outlet is in the form of a cap 24 fixed on the top of the casing 13 and extending over the top of the settling tank. This casing is provided with a bracket 25 for supporting 45 the upper end of the shaft 17 and another bracket 26 for supporting the idler pulleys 27. In other words it carries the immediate driving mechanism for the shaft 17. The step can be kept lubricated by any ordinary 50 compression grease cup 28 on the outside of the casing and the lower end of the casing is provided with a hand hole 29 which can be opened for cleaning purposes and repairs. In this way the liquor is discharged 55 from the catch basin and delivered into the settling tank with an easy, steady, and uniform flow incapable of causing agitation,

churning, and foaming and by a mechanism which does not involve any valves or other small parts likely to get clogged up by sediment and fibers. 60

Although I have illustrated and described only a single embodiment of the invention, I am aware of the fact that modifications can be made therein by any person skilled 65 in the art without departing from the scope of the invention as expressed in the claims. Therefore I do not wish to be limited in these respects but

What I do claim is:—

1. The combination with a tank, a catch basin, and a settling tank for delivering liquor into the tank, of a pipe leading from said catch basin, a stationary vertical cylinder located adjacent to said settling tank 75 and having an in-take above the bottom thereof into which said pipe extends, a vertical shaft supported on the bottom of said cylinder and extending up through the top thereof, and a helical blade about said shaft 80 and adapted to rotate therewith, said blade extending down below the outlet of the catch basin whereby the water from the catch basin will enter the bottom of said casing and stand therein normally and be 85 lifted without foaming or churning when the shaft is rotated, said casing having an outlet delivering into the top of the settling tank.

2. In a device of the character described, 90 the combination of a cylindrical casing, a rotatable screw in said casing made up of a plurality of sections each having a blade constituting one convolution of a helix, and means for rotating said screw. 95

3. In a device of the character described, the combination of a stationary vertical cylindrical casing having an inlet above the bottom thereof, a vertical rotatable screw in said casing extending below the bottom of 100 said inlet, made up of a plurality of sections each having a blade constituting one convolution of a helix, the edge of the blade of the lowest section being sharpened, means for rotating said screw, and an outlet from 105 said casing at the top of said screw.

In testimony whereof I have hereunto set my hand, in the presence of two subscribing witnesses.

FREDERICK G. SARGENT.
